UNITED STATES PATENT OFFICE.

ALFRED PEARCE-TOWL, OF OXFORD, ENGLAND.

GAS-COOKING RING WITH MEANS FOR CONTROLLING GAS SUPPLY BY A KETTLE, SAUCEPAN, OR THE LIKE.

1,385,763.

Specification of Letters Patent. Patented July 26, 1921.

Application filed July 14, 1920. Serial No. 396,289.

To all whom it may concern:

Be it known that I, ALFRED PEARCE-TOWL, a subject of the King of Great Britain and Ireland, and a resident of Oxford, county of 5 Oxford, England, have invented a certain new and useful Improvement in Gas-Cooking Rings with Means for Controlling Gas Supply by a Kettle, Saucepan, or the like, (for which I have filed an application in 10 Great Britain, No. 142,276, April 16, 1919, Patent No. 142,276,) of which the following is a specification.

This invention relates to gas-cooking rings of the type in which the supply of gas 15 to a mixing chamber at or near the point of combustion is cut off, when the kettle, saucepan or the like is removed from off said rings, there being provided a by-pass to the burner to ignite the mixture when 20 the kettle or the like is in position. The said invention relates more particularly to a gas-cooking ring of the foregoing type wherein is employed an arrangement of valve, and means operating same under the 25 action of the kettle or the like, whereby a variable supply of gas is possible, regulated by the placing on, disposition of and removal of the said kettle from the said valve-actuating means.

30 The present invention consists chiefly of means for carrying the foregoing into effect, consisting of a rotary valve with different radial bores in an inner fixed member, which bores are brought into alignment with 35 their respective exits (to mixture chamber) in an outer concentric rotary member by means of a stud or studs, upon which presses a pivoted lever, levers, or equivalents, so shaped that it or they may partially or completely 40 depress the stud or studs according to the movement of the kettle or the like as aforesaid. Various improved constructional features of the ring are also carried out according to this invention.

45 To render the invention clear, two sheets of drawings are appended, illustrating such an embodiment of the said invention; and in said drawings:—

Figure 1 is a sectional elevation of a portion of a gas-ring.

Fig. 2 is a fragmentary view with por-

tions broken away, looking in the direction of arrow in Fig. 1.

Fig. 3 is an end view of a regulator device; and,

Fig. 4 a side view thereof; and,

Fig. 5 a section thereof, taken on the line x, x—Fig. 3.

In the form of the invention shown in the accompanying drawings, the gas regulator 60 or valve is designated in its entirety by a, the same being located within the gas ring b at the junction of the tubular inlet extension c, and through which the gas supply pipe f passes as clearly shown in Fig. 1. 65 The portion of the gas supply pipe f which projects into the valve chamber of the ring provides a convenient support for the regulator or valve device a, and the arrangement and construction of the said valve device is such that the same may be automatically 70 operated or shifted by a superposed utensil actuated device to control the passage of gas into the gas ring. That is to say, the regulator or valve a is so constructed 75 and arranged as to be normally closed, but means are provided whereby when a kettle or other utensil is placed upon the grate above the gas ring, the valve will be opened to a greater or less extent to permit 80 of more or less gas entering the burner ring from the supply pipe. In this connection, it will be understood that the position of the utensil with reference to the valve actuating means controls the amount of gas supply 85 as may be seen by the dotted lines indicating various positions of the kettle with reference to the valve actuating means.

The burner ring b is preferably provided in the well known manner with an air inlet 90 d so that mixing of air and gas takes place upon the immediate issuance of the gas from the valve or regulator a, leaving no appreciable space to cause a blow-back by pre-ignition, as frequently happens where 95 the valve is located a considerable distance from the air mixer. Also a gas by-pass e having a pilot light may be arranged at any suitable and convenient place to ignite the burner when the valve a is actuated by the 100 placing of a utensil thereover.

Referring now more particularly to the

construction of the valve α and its actuating instrumentalities, it will be observed from Fig. 5 that the said supply pipe f is threaded at its outlet end to receive an interiorly threaded collar g having suitable radial openings k and l registering with openings in the wall of the pipe f to provide lateral gas discharge ports. The collar g constitutes a relatively fixed valve body and rotatably supports a flanged ring or cap h having a suitable slot in its side wall for progressively uncovering the gas discharge ports k and l when shifted by the utensil operated means to be presently referred to more in detail. The flanged ring or cap h is preferably engaged by a supplemental cap member i having a weighted portion m for normally rotating the relatively movable part $h-i$ so that the ports thereof will be out of registry with the ports k and l of the collar g . As shown in Fig. 5, the flanged ring or cap h may be provided with the rib j for fitting in a groove portion of the collar g to insure a gas-tight joint between the rear end of the relatively movable valve member and the relatively fixed valve part.

The upper portion of the rotatable valve casing $h-i$ carries an arm n adapted to engage with the lower end of a vertically movable stud o , shown in Figs. 1 and 2, and which stud is adapted to be engaged by the lower edge of a depressible lever t which is pivoted in the supporting web p as indicated at q in such a manner that its relatively free end r will project above the plane of the utensil seating position. The said portion r of the lever t is formed in such a manner that the same may be progressively engaged by the bottom edge of a utensil to be depressed from the position t^2 Fig. 1 to the position t' or the position t , or any intermediate position to expose or uncover more openings of the collar g through the slot in the wall of the member h .

When a "full" light is desired, the kettle is placed on the burner so as to fully depress the stud which rotates the sleeve h to its fullest extent and brings into operation the large gas exit k ; while partial depression in the manner hereinafter described causes the smaller holes l to register allowing a limited supply of gas. Removal of the kettle frees the stud, whereupon the regulator sleeve may revolve to its normal and closed position "gas off" by the action of the weight m .

In conjunction with the stud o there is employed an actuating lever t , pivoted near one side of its lower edge to the upstanding support web p of the gas ring, at the pivot q . This lever has one portion r of its upper edge inclined obtusely to the remaining portion, so that by sliding the kettle or the link s in a direction opposite to the arrows

in Fig. 1, the lever is free to rise under the action of the weight m from the "full on" position to the "simmer" position (shown in dot-and-dash lines t^1) by reason of the weight m carrying around the cap h to the simmer position. On removing the kettle, the lever assumes the position t^2 and the gas is cut off because the cap h has rotated correspondingly to the position indicated by the weight position m —Fig. 2.

I claim:

1. An automatic gas supply device for burner rings including in combination with the burner ring and fuel supply pipe, a valve carried by the fuel supply pipe, and an operator for the valve projecting above the plane of seating of a utensil above the burner and having a portion adapted to be progressively engaged by the utensil to variably control the valve.

2. An automatic gas supply device for burner rings including in combination with the burner ring and fuel supply pipe, a valve device carried by the end of the fuel supply pipe, means for automatically maintaining said valve device closed, and utensil actuated means including a lever having a relatively inclined portion normally projecting above the plane of the utensil seating position and adapted to be depressed as the utensil is shifted laterally along said inclined edge to open the valve.

3. An automatic gas supply device for burner rings including in combination with the burner ring and fuel supply pipe, a valve device carried by the end of the fuel supply pipe, means for normally maintaining said valve closed, a vertically slid able stud engaging a portion of said valve, and lever means for depressing said stud to actuate said valve, said lever means comprising a lever having a relatively inclined face normally projecting above the utensil seating position and adapted to be progressively depressed by the utensil to regulate the operation of the valve.

4. An automatic gas supply device for burner rings including in combination with the burner ring and fuel supply pipe, a valve device including a relatively rotatable valve member having a slot, a relatively fixed valve member having a plurality of gas discharge outlets adapted to be progressively uncovered by the slot in the rotatable valve, and utensil depressed means for shifting said rotatable valve member.

5. An automatic gas supply device for burner rings including in combination with the burner ring and fuel supply pipe, a valve device including a relatively rotatable valve member having a slot, a relatively fixed valve member having a plurality of gas discharge outlets adapted to be progressively uncovered by the slot in the rotatable

valve, and utensil depressed means for shifting said rotatable valve member, said means including a lever having a progressively inclined utensil engaging edge normally projecting above the plane of the utensil seating surface and adapted to be progressively depressed by the utensil to rotate the rela-

tively movable part of the valve to uncover a greater number of ports in the relatively fixed valve member.

In testimony whereof I have affixed my signature hereto this 25th day of June, 1920.

ALFRED PEARCE-TOWL.
